DESIGN FOR A BOTTLE

William A. Nester, East St. Louis, Ill., assignor to
Obear-Nester Glass Company, St. Louis, Mo., a
corporation of Missouri

Application April 18, 1934, Serial No. 51,443

Term of patent 14 years

To all whom it may concern:

Be it known that I, WILLIAM A. NESTER, a citizen of the United States, residing at East St. Louis, county of St. Clair, State of Illinois, have invented a new, original, and ornamental Design for a Bottle, substantially as shown in the accompanying drawing, in which—

Fig. 1 is a plan view of a bottle embodying my new design.

Fig. 2 is a front (or rear) elevation, the side of the bottle opposite that shown in this figure being of identically the same appearance.

Fig. 3 is a side elevation.

I claim:

The ornamental design for a bottle substantially as shown and described.

WILLIAM A. NESTER.
